DESIGN FOR A MULTIPLE LETTER TRAY

Robert J. Thorn and Theodore Hess, Chicago,
Ill.; said Hess assignor to said Thorn

Application July 8, 1939, Serial No. 85,922

Term of patent 14 years

To all whom it may concern:

Be it known that we, Robert J. Thorn and Theodore Hess, both citizens of the United States and residents of Chicago, in the county of Cook and State of Illinois, have invented a new, original, and ornamental Design for a Multiple Letter Tray, of which the following is a specification, reference being had to the accompanying drawing, forming part thereof.

The figure is a perspective view of the letter tray having two shelves, showing our new design. The left-hand portion of the tray, not shown, is identical to the right-hand portion.

We claim:

The ornamental design for a multiple letter tray, as shown and described.

ROBERT J. THORN.
THEODORE HESS.
